[57] CLAIM

The ornamental design for a pouch for smoking materials, as shown and described.

DESCRIPTION

FIG. 1 is a side elevational view of a pouch for smoking materials, showing my new design;
FIG. 2 is an elevational view of the opposite side thereof;

FIG. 3 is a top plan view thereof; and,

FIG. 4 is an elevational view of the left end of FIG. 1.
The zipper pattern which is fragmentarily shown in FIG. 3 is understood to repeat uniformly and continuously along the entire indicated length.
